UNITED STATES PATENT OFFICE.

GOTTLIEB JAHN, OF KIEL, AND ARTHUR RUNKWITZ, OF ELENSCHENHAGEN, NEAR KIEL, GERMANY, ASSIGNEES TO FRIED. KRUPP GERMANIAWERFT AKTIENGESELLSCHAFT, OF KIEL-GAARDEN, GERMANY.

HORIZONTAL WASTE-GAS STEAM BOILER.

Application filed April 3, 1926, Serial No. 99,534, and in Germany August 13, 1925.

This invention relates to the heating of auxiliary steam boilers of the horizontal type and has for its object to heat such boilers with the exhaust gases of internal 5 combustion engines utilizing to a high degree the heat contained in the gases.

According to the invention, this object is attained by arranging an exhaust gas distributing chamber so as to partly surround 10 the intake chamber of the auxiliary steam boiler and by causing the introduction of the exhaust gases from the distributing chamber into the intake chamber to take place through nozzles which extend through 15 the shell of the intake chamber at different angles in such a manner that the nozzles break up the exhaust gas current into a plurality of divisional currents and impart to the latter a circular movement, thereby 20 effecting a uniform distribution of the exhaust gases over the entire head face of the boiler.

An embodiment of the subject-matter of the invention is illustrated by way of example in the accompanying drawing in 25 which:

Fig. 1 is a vertical longitudinal section through the boiler and

Fig. 2 is a section on the line 2—2 of 30 Fig. 1.

A is the horizontal cylindrical auxiliary steam boiler through which extend the heating tubes B which are rolled into the head walls of the boiler. Arranged in front of 35 the boiler is an intake chamber C and in its rear a smoke chamber D from which the heating gases pass through a branch d' into the chimney (not shown). Arranged outside the intake chamber C is a distributing 40 chamber E from which nozzles F open into the intake chamber. These nozzles extend through the shell of the intake chamber at angles different from one another, the arrangement being such that the angles of the 45 axes of the several nozzles with respect to the horizontal continually increase from the inlet branch e' for the exhaust gases.

The inlet branch e', which is in connection with the exhaust conduit of the internal 50 combustion engine, admits the exhaust gases

into the distributing chamber E where they distribute throughout the entire space of the chamber. From the distributing chamber the gases flow in divisional currents through the nozzles F into the intake chamber C into which the heating tubes open. The arrangement of the nozzles F prevents the divisional currents from spreading irregularly in the intake chamber C. On the one hand, these nozzles F impart to the several divisional exhaust gas currents a circular movement in the interior of the intake chamber C and, on the other hand, the divisional exhaust gas currents are guided in almost concentrical circles around the point α in Fig. 2, the divisional current admitted through the nozzle 1 describing the smallest circle around the point α and each of the next following nozzles 2, 3 etc. causing its divisional current to circulate around the point α with a correspondingly larger radius. It is attained by this concentric guiding of the divisional exhaust gas currents that all heating tubes B are uniformly supplied with exhaust gases. The exhaust gases flowing through the heating tubes deliver their contents of heat to the boiler water and then pass into the smoke chamber D and from the latter through the branch d' into the chimney.

The described manner of the distribution permits of an excellent utilization of the heat of the exhaust gases to be attained.

The plant is more particularly adapted for use on ships propelled by internal combustion engines.

We claim:

A horizontal waste gas steam boiler, comprising heating tubes extending from one head wall of the boiler to the other, an intake chamber arranged on one of the head faces of the boiler so as to communicate with the heating tubes, a waste gas distributing chamber arranged to partly surround the intake chamber, means for introducing a current of waste gas into the distributing chamber, and nozzles in the shell of the intake chamber for establishing communication between the distributing chamber and the intake chamber and breaking up the waste gas

current into a plurality of divisional currents, the said nozzles being arranged to extend through the shell of the intake chamber at angles different from one another in such a manner that the nozzles impart to the divisional currents substantially concentric circular movements each of different radius in the intake chamber and thereby effect a

uniform distribution of the waste gas over the entire head face of the boiler. 10

The foregoing specification signed at Hamburg, Germany, this 19th day of February, 1926.

GOTTLIEB JAHN.
ARTHUR RUNKWITZ.
